UNITED STATES PATENT OFFICE.

HERBERT CLIFTON ALLEN, OF RICHMOND, VIRGINIA.

ETCHING-MACHINE.

1,389,284.

Specification of Letters Patent. Patented Aug. 30, 1921.

Application filed July 6, 1920. Serial No. 394,322.

To all whom it may concern:

Be it known that I, HERBERT C. ALLEN, a citizen of the United States, residing at Richmond, in the county of Henrico and State of Virginia, have invented certain new and useful Improvements in Etching-Machines; and I do declare the following to be a full, clear, and exact description of the invention, such as will enable others skilled in the art to which it appertains to make and use the same.

This invention relates to machines adapted to mechanically remove the surface coating from a plate to be etched, the actual removal of the metallic face of the plate being accomplished in an acid bath in the usual well known manner.

The invention is an improvement upon Patent 1,039,713, granted October 1, 1912 to W. S. Eaton, the improvements residing particularly in the mechanism by which a needle which operates upon the surface of the plate to be etched is moved in and out of engagement with the plate.

In the machine disclosed by the Eaton patent and in other similar types of machines a stylus is operated by a hand movement over a pattern or master plate and this causes a corresponding movement of a needle over the prepared work plate, the needle being moved into and out of engagement with the work plate by a foot movement which is altogether independent of the hand movement of the stylus over the pattern plate. In order to obtain a high degree of excellence of the work produced by such a machine, considerable practice is necessary to produce the necessary skill. The present invention eliminates the foot movement which moves the needle in and out of engagement with the work plate and makes the required movement of the needle automatic upon the movement of the stylus in and out of engagement with the pattern plate. It will thus be seen that the improved machine can be operated by unskilled labor and without first requiring considerable practice and experience.

The automatic movement of the needle in and out of engagement with the work plate is accomplished by electromagnetic means, the circuit of which includes the stylus and pattern plate which are arranged to permit the needle to drop by gravity into engagement with the work plate when the stylus is moved by hand into engagement with the pattern plate.

Various ways in which to electromagnetically operate the needle may be employed, but it is preferable to employ the important feature of invention wherein primary and secondary circuits are used, the primary circuit including the stylus and pattern plate and being comparatively weak so that no appreciable amount of sparking will occur when closing or opening this circuit by engagement or disengagement with the pattern plate.

With the above and other aims and objects in view, the invention consists of the novel features of construction, and the combination and arrangement of parts as are hereinafter fully described and claimed.

The accompanying drawings illustrate the practical embodiments of the invention. In these drawings, Figure 1 is a side elevation of a machine constructed in accordance with the invention.

Fig. 2 is a front elevation of the machine.

Fig. 3 is a diagrammatic view illustrating the circuit arrangement of the improved mechanism.

Fig. 4 is a detail sectional view taken substantially on the line 4-4 of Fig. 1.

Fig. 5 is a plan view of the magnet which is employed to move the needle out of engagement with the work plate and showing particularly the mounting for the magnet.

Fig. 6 is an end view of the relay which is employed in the improved mechanism.

Fig. 7 is a top view of the relay.

Fig. 8 is a side elevation of the machine equipped with a modified form of mechanism for moving the needle in and out of engagement with the work plate.

Fig. 9 is a diagrammatic view illustrating the circuit arrangement of the modified form.

Fig. 10 is a top view of the relay used in the modified form.

In the drawings, especially in Figs. 1, 2 and 8, an etching machine constructed similar to the machine disclosed in the above mentioned Eaton patent is conventionally illustrated, the numeral 1 designating the supporting framework of the machine which includes upright boards 2 and a top plate 3, the latter being made in the usual manner

out of wood. Bolted or otherwise suitably secured to the top plate 3 and rising vertically therefrom is a column 4, the upper end portion of which supports a fixed frame 5 and a fixed work bed 6. This work bed 6 is provided with suitable means 7 designed for receiving and holding in place a work plate 8, the latter having a metallic face provided with a surface coating adapted to have portions removed to allow the exposed portions of the metallic face to be subjected to the action of an acid bath in the usual and well known manner.

Movably mounted upon the fixed frame 5 is a carriage 9. One end of the carriage 9 is provided with an upstanding lug 10 which fits into the bottom or intermediate portion of a substantially U-shaped bracket or yoke 11. The spaced arms of this bracket 11 adjacent their lower connected ends are provided with pintles 12 which form the pivot of an arm 13. The pivot of this arm 13 is nearer to one end of said arm than to the other, and the longer part is provided at its end with a needle 14 operable over the work plate 8. The arm 13 is consequently overbalanced to the position where the needle 14 is in engagement with the work plate 8. The upper ends of the arms of the bracket 11 are provided with aligned pintles 15 which serve as a pivot for a plate 16. This plate 16 carries an electromagnet 17, the magnetic core 18 of which extends through an opening in the plate and is provided with a locking nut 19. The lower extremity of the core 18 is disposed a short distance above the upper edge of the arm 13 and in alinement with a magnetic plate 20 mounted thereon. The arm 13 when attracted by the magnet 17 will be held in a raised position so that the needle 14 is out of engagement with the work plate 8, but when the magnet 17 is deenergized the arm 13 will drop by gravity so that the needle 14 will engage the plate 8. The magnet 17 being carried by the pivotally hung plate 16 may be moved rearwardly and upwardly away from the arm 13, but when it is disposed in its normal position the plate 16 rests upon inwardly extending lugs 21 which are formed integral with the arms of the bracket 11 at the upper extremities of said arms. The bracket 11 is locked to the aforementioned lug 10 by means of a set screw 22.

In order that the arm 13 may be held and locked in its raised position with the needle 14 out of engagement with the work plate 8, the forward side of the bracket 11 has pivotally mounted thereon a cam lever 23 engageable with the arm.

Mounted upon the column 4 is a sleeve 24 having a yoke 25 to which is hung so as to have a universal movement a transmitter or arm 26. The transmitter 26 is hung upon the yoke 25 at a point between its ends.

The upper end of the transmitter 26 is engaged with the carriage 9 in such a manner that whenever the transmitter 26 is moved, the carriage 9 will be shifted. The lower end of the transmitter 26 carries a stylus 27 which is operable over a master or pattern plate 28 carried in a holder 29 mounted upon the top plate 3 of the supporting framework. The top plate 3 being constructed of wood is necessarily insulated from the metal column 4 and metal parts of the machine supported and carried thereby.

All of the parts above described with the exception of the electromagnet 17, bracket 11 and possibly the cam lever 23 are constructed similar to the machine disclosed in the Eaton patent. This patent in addition to these parts discloses a foot operated rod for raising the arm 13 so that the needle 14 is held out of engagement with the work plate 8. This rod has been omitted from the present invention and the same result is accomplished by means of the magnet 17.

One terminal of the magnet 17 is connected by a conductor 30 leading to suitable source of electric current. The other terminal of the magnet 17 is connected by the conductor 31 to an adjustable relatively fixed contact 32 of a relay mechanism 33 which is mounted upon one of the side boards 2 of the supporting frame work 1. The numeral 34 designates the movable armature of the relay. This is pivoted in any suitable manner at one end upon a suitable bracket 35 and is normally maintained in engagement with the contact 32 by means of a spring 36, one end of which is engaged by a set screw 37 mounted upon a bracket fixed to the base of the relay. The pivoted end of the armature 34 is connected by a conductor 38 to a spark condenser 39, which in turn, is connected by a conductor 40 to the source of current. This circuit is comparatively strong so that the magnet 17 when energized will have strength sufficient to raise the arm 13 to the position where the needle 14 is out of engagement with the work plate 8. This circuit may be termed the "major circuit."

The other parts of the relay 33 consist of a pair of electromagnets 41 arranged to operate in unison and mounted upon a suitable bracket carried by the base of the relay. One terminal of this pair of magnets 41 is connected by a conductor 42 to the set screw 43 which holds the master or pattern plate 28 upon the top plate 3 of the supporting frame work 1 so that an electric connection is made to the master or pattern plate 28. The other terminal of this pair of magnets 41 is connected by a conductor 44 to one pole of a battery 45, the other pole of which is connected by a conductor 46 to the securing post 47 of the column 4 so that an electric connection is made to the stylus 27 through the medium of the metal 130

parts of the machine carried and supported by the column 4. This circuit may be termed the "primary" or "minor circuit."

In using the machine above described, assuming that the work plate 8 is clamped in place, that the master or pattern plate 28 is clamped in place, and that the machine has been adjusted to reproduce the design of the master or pattern plate in the desired 10 size upon the work plate, it is only necessary for the operator to move the stylus 27 into contact with the master or pattern plate 28 and trace the lines or design thereon. In doing so the stylus will be brought in and 15 out of engagement with the master or pattern plate. Every time the stylus engages the pattern plate the primary or minor circuit is closed, the current passing from battery 45 through conductor 46, the metal parts 20 of the machine, stylus 27, pattern plate 28, conductor 42, magnets 41 and conductor 44 back to the battery. The primary or minor circuit being closed, the magnets 41 will be energized so as to lift the armature 34 out of 25 engagement with the fixed contact 32. Normally the armature 34 is in engagement with the contact 32 so that the major or secondary circuit is closed, thus causing the magnet 17 to be energized and holding the arm 30 13 to the position where the needle 14 is out of engagement with the work plate 8. When the magnet 17 is deenergized the armature 34 is raised out of engagement with the contact 32, the arm 13 will drop by gravity 35 to the position where the needle 14 is in engagement with the work plate 8. It will thus be seen that the raising and lowering of the arm 13 carrying the needle 14 out and in engagement with the work plate 40 40 is entirely automatic upon the movement of the stylus 27 out and in engagement with the pattern plate 28. The primary or minor circuit having the battery 45 as a source of current is comparatively weak so that no 45 shock will be obtained in operating the machine and so that no sparking will occur or fusing will take place when the stylus 27 is brought into and out of engagement with the pattern plate 28. The spark condenser 50 39 arranged in the secondary or major circuit serves to prevent an appreciable amount of sparking to take place between the armature 34 and fixed contact 32 when the armature is moved in and out of engagement 55 with the contact.

In the modified form of the invention shown in Figs. 8, 9 and 10 the same reference numerals are used to indicate the usual parts of the Eaton etching machine as are used in the other figures of the drawings. In this modified form the bracket 11 has been eliminated and in its place is used the ordinary bracket 11' of the Eaton machine. The arm 13 is constructed similar 60 to and pivoted to the bracket 11' in the

manner disclosed by the Eaton patent. In this case a lifting rod 48 is employed. This lifting rod 48 is similar to the lifting rod employed in the Eaton machine as it engages the lower side of the arm 13 and under the tension of the spring 49 normally holds the arm 13 so that the needle 14 is out of contact with the work plate 8. Instead of having the rod 48 connected to a foot treadle as in the Eaton patent, the 70 lower end of this rod is provided with a magnetic head 50 arranged directly above the upper end of the magnetic core 51 of an electromagnet 52 which is carried by the bracket 53 mounted upon one of the side 75 boards 2 of the framework 1.

In this form of the invention a relay 33' is used, the pair of magnets 41' of which have one of their terminals connected by conductor 42' to the pattern plate 28, while 80 their other terminal is connected by the conductor 44' to one pole of a battery 45', the other pole of which is connected by a conductor 46' to the body of the column 4 and through the metal parts of the machine 85 to the stylus 27. This circuit is substantially the same as the primary or minor circuit in the first described form of the invention.

The secondary or major circuit in the modified form includes the electromagnet 90 52. One terminal of this is connected by a conductor 30' to a source of current, while the other terminal is connected by a conductor 31' to a spark condenser 39' which in turn is connected by a conductor 38' to the 95 bracket 35' upon which an armature 34' is pivotally mounted. The free end of the armature 34' is engageable with an adjustable relatively fixed contact 32', which is connected by a conductor 40' to the source of current of the major circuit. Under normal 100 conditions, that is, when the primary or minor circuit is open so that the magnets 41' are deenergized, armature 34' is out of engagement with the contact 32' under the 105 tension of set screw 37' acting against spring 36' so that the major circuit is also open and the magnet 52 is deenergized. Under these 110 conditions, the spring 49 maintains the rod 48 in raised position so that the arm 13 is 115 raised with its needle 14 out of engagement with the work plate 8. When, however, the operator moves the stylus 27 into engagement with the pattern plate 28 the primary or minor circuit is closed, thus energizing the 120 magnets 41 and lifting the armature 34' into engagement with the contact 32'. This movement of the armature 34' closes the secondary or major circuit and energizes the 125 magnet 52. The energization of the magnet 52 will draw the rod 48 downwardly against the tension of the spring 49 and permit the arm 13 to drop by gravity to the position where the needle 14 engages the work plate 8. The instant the stylus 27 is raised from 130

- the pattern plate 28 the primary circuit will be opened, which condition will permit the armature 34' to break the secondary or major circuit, thus deenergizing the magnet 52 and 5 permitting the rod 48 to raise the arm 13. The primary circuit being comparatively weak as in the previous case will not permit sparking to occur when the stylus 27 is moved into and out of engagement with the 10 pattern plate 28, and the spark condenser 39 will not permit an appreciable amount of sparking between the armature 34' and contact 32' as the armature is moved into and out of engagement with the contact.
- 15 From the foregoing description, taken in connection with the accompanying drawings, it will be seen that the objects of the invention have been effectively carried out. The movement of the needle in and out of engagement with the work plate is entirely automatic and instantaneous by reason of the fact that it is controlled solely by the movement of the stylus in and out of engagement with the pattern plate. The necessity 20 of a foot operated treadle has entirely been dispensed with. The operation of the improved machine is easy and perfect work may be turned out by unskilled labor without first requiring considerable practice.
- 25 Furthermore, a greater output may be obtained by using the improved machine than could be obtained by using the usual type of machine.
- It is obvious that numerous changes in 30 form, proportion, and in the minor details of construction may be resorted to without departing from the underlying principles of the invention as defined in the appended claims:
- 35 1. In a machine of the class described, the combination of a work bed adapted to hold a work plate, a holder adapted to hold a pattern plate, a needle operable upon the work plate and movable in and out of engagement therewith, a stylus operable upon the pattern plate and movable in and out of engagement therewith, mechanism associated with said stylus and said needle for causing said needle to operate upon said work plate upon movement of said stylus upon said pattern plate, means for moving said needle in and out of engagement with said work plate and including an electromagnet, the circuit of said magnet including said stylus and said pattern plate whereby said circuit is controlled by movement of said stylus in and out of engagement with said pattern plate. 70
- 40 2. In a device of the class described, the combination of a work bed for holding a work plate, a holder for holding a pattern plate, a needle operable upon the work plate and movable in and out of engagement therewith, a stylus operable upon the pattern plate and movable in and out of engagement therewith, means associated with said needle and said stylus for operating said needle upon said work plate upon movement of said stylus upon said pattern plate, electromagnetically operated means for moving said needle in and out of engagement with said work plate, a circuit for said means, a relay 80 having its armature arranged in said circuit, a second circuit including the electromagnets of said relay and said stylus and said pattern plate, whereby said second circuit is controlled by the movement of said stylus in and out of engagement with said pattern plate. 85
- 45 3. In a device of the class described, the combination of a work bed for holding a work plate, a holder for holding a pattern plate, a needle operable upon the work plate and movable in and out of engagement therewith, a stylus operable upon the pattern plate and movable in and out of engagement therewith, means associated with said needle and said stylus for operating said needle upon said work plate upon movement of said stylus upon said pattern plate, a normally energized electromagnet for normally holding said needle out of engagement with said work plate, said magnet when deenergized permitting said needle to move into engagement with said work plate, and means operable when said stylus is moved into engagement with said pattern plate to deenergize said magnet. 90
- 50 4. In a machine of the class described, the combination of a work bed for holding a work plate, a holder for holding a pattern plate, a needle operable upon the work plate and movable in and out of engagement therewith, a stylus operable upon the pattern plate and movable in and out of engagement therewith, means associated with said needle and said stylus for operating said needle upon said work plate upon movement of said stylus upon said pattern plate, a normally energized electromagnet for normally holding said needle out of engagement with said work plate, said magnet when deenergized permitting said needle to move into engagement with said work plate, and means operable when said stylus is moved into engagement with said pattern plate to deenergize said magnet. 100
- 55 5. In a machine of the class described, the combination of a work bed for holding a work plate, a holder for holding a pattern plate, a needle operable upon the work plate and movable in and out of engagement therewith, a stylus operable upon the pattern plate and movable in and out of engagement therewith, means associated with said needle and said stylus for operating said needle upon said work plate upon movement of said stylus upon said pattern plate, a normally energized electromagnet for normally holding said needle out of engagement with said work plate, said magnet when deenergized 110
- 60 6. In a machine of the class described, the combination of a work bed for holding a work plate, a holder for holding a pattern plate, a needle operable upon the work plate and movable in and out of engagement therewith, a stylus operable upon the pattern plate and movable in and out of engagement therewith, means associated with said needle and said stylus for operating said needle upon said work plate upon movement of said stylus upon said pattern plate, a normally energized electromagnet for normally holding said needle out of engagement with said work plate, said magnet when deenergized 115
- 65 7. In a machine of the class described, the combination of a work bed for holding a work plate, a holder for holding a pattern plate, a needle operable upon the work plate and movable in and out of engagement therewith, a stylus operable upon the pattern plate and movable in and out of engagement therewith, means associated with said needle and said stylus for operating said needle upon said work plate upon movement of said stylus upon said pattern plate, a normally energized electromagnet for normally holding said needle out of engagement with said work plate, said magnet when deenergized 120
- 70 8. In a machine of the class described, the combination of a work bed for holding a work plate, a holder for holding a pattern plate, a needle operable upon the work plate and movable in and out of engagement therewith, a stylus operable upon the pattern plate and movable in and out of engagement therewith, means associated with said needle and said stylus for operating said needle upon said work plate upon movement of said stylus upon said pattern plate, a normally energized electromagnet for normally holding said needle out of engagement with said work plate, said magnet when deenergized 125
- 75 9. In a machine of the class described, the combination of a work bed for holding a work plate, a holder for holding a pattern plate, a needle operable upon the work plate and movable in and out of engagement therewith, a stylus operable upon the pattern plate and movable in and out of engagement therewith, means associated with said needle and said stylus for operating said needle upon said work plate upon movement of said stylus upon said pattern plate, a normally energized electromagnet for normally holding said needle out of engagement with said work plate, said magnet when deenergized 130

- permitting said needle to move into engagement with said work plate, a circuit for said magnet, said circuit including a normally closed switch, a second circuit including said stylus and said pattern plate and closed and opened by the engagement and disengagement respectively of said stylus with said pattern plate, and electromagnetic means included in said second circuit for opening said switch when said second circuit is closed.
6. In a machine of the class described, the combination of a work bed for holding a work plate, a holder for holding a pattern plate, a needle operable upon the work plate and movable in and out of engagement therewith, a stylus operable upon the pattern plate and movable in and out of engagement therewith, means associated with said needle and said stylus for operating said needle upon said work plate upon a movement of said stylus upon said pattern plate, a normally energized electromagnet for normally holding said needle out of engagement with said work plate, said magnet when deenergized permitting said needle to move into engagement with said work plate, a circuit for said magnet, said circuit including a normally closed switch, a second circuit including said stylus and said pattern plate and closed and opened by the engagement and disengagement respectively of said stylus with said pattern plate, and electromagnetic means included in said second circuit for opening said switch when said second circuit is closed, said second circuit being comparatively weak so that no sparking will occur when said stylus is engaged and disengaged with said pattern plate.
7. In a machine of the class described, the combination of a work bed for holding a work plate, a holder for holding a pattern plate, a needle operable upon the work plate and movable in and out of engagement therewith, a stylus operable upon a pattern plate and movable in and out of engagement therewith, means associated with said needle and said stylus for moving said needle upon said work plate as said stylus is moved upon said pattern plate, a major circuit, an electromagnet arranged in said major circuit for holding said needle out of engagement with said work plate, a minor circuit including said stylus and said pattern plate, said minor circuit being closed when said stylus is moved into engagement with said pattern plate, and a relay, the magnets of which are included in said minor circuit while its armature is included in said major circuit.
8. In a machine of the class described, the combination of a work bed for holding a work plate, a holder for holding a pattern plate, a needle operable upon the work plate and movable in and out of engagement therewith, a stylus operable upon the pattern plate and movable in and out of engagement therewith, means associated with said needle and said stylus for moving said needle over said work plate as said stylus is moved over said pattern plate, a pivotally mounted arm upon which said needle is carried, a magnetic plate fixed to said arm, an electromagnet mounted upon the machine and disposed above said magnetic plate whereby to hold said arm in the position where said needle is out of engagement with said work plate, a circuit for said magnet, and means for opening said circuit upon engagement of said stylus with said pattern plate.
9. In a machine of the class described, the combination of a work bed for holding a work plate, a holder for holding a pattern plate, a movable carriage, a stylus operable upon said pattern plate and movable in and out of engagement therewith, means associated with said stylus and said carriage for moving said carriage upon movement of said stylus upon said pattern plate, a bracket carried by said carriage, an arm pivoted to said bracket, a needle carried by said arm and operable upon said work plate, a supporting plate pivotally mounted upon said bracket, an electromagnet carried by said supporting plate for holding said arm in the position where said needle is out of engagement with said work plate, means carried by said bracket for maintaining said supporting plate in the position where said magnet is disposed in operative relation with respect to said arm, said means permitting said supporting plate and said magnet to be swung out of operative position with said arm, a circuit for said magnet, and means for opening said circuit when said stylus is moved into engagement with said pattern plate.
10. In a machine of the class described, the combination of a stylus arm, a primary electric circuit operable by said stylus arm, an electric relay controlled by said primary circuit, a needle arm, a secondary electric circuit controlled by said relay, and electric means in said secondary circuit for operating said needle arm.

In testimony whereof I have hereunto set my hand.

HERBERT CLIFTON ALLEN.

Corrections in Letters Patent No. 1,389,284.

It is hereby certified that in Letters Patent No. 1,389,284, granted August 30, 1921, upon the application of Herbert Clifton Allen, of Richmond, Virginia, for an improvement in "Etching-Machines," errors appear in the printed specification requiring correction as follows: Page 1, line 60, for the word "is," first occurrence, read *it*; page 3, line 32, after the word "deenergized" insert the word *when*, and that the said Letters Patent should be read with these corrections therein that the same may conform to the record of the case in the Patent Office.

Signed and sealed this 15th day of November, A. D., 1921.

[SEAL.]

KARL FENNING,

Acting Commissioner of Patents.
